UNITED STATES PATENT OFFICE.

GEORGE S. CLARK, OF KALAMAZOO, AND PLUMMER B. SNYDER, OF EAST LANSING,
MICHIGAN; SAID CLARK ASSIGNOR TO SAID SNYDER.

DESIGN FOR A THERMOMETER.

59,333.

Specification for Design.

Patented Oct. 11, 1921.

Application filed April 16, 1921. Serial No. 462,034. Term of patent 14 years.

To all whom it may concern:

Be it known that we, GEORGE S. CLARK, a citizen of the United States, residing at the city and county of Kalamazoo, State of Michigan, and PLUMMER B. SNYDER, a citizen of the United States, residing at East Lansing, county of Ingham, State of Michigan, have invented a new, original, and ornamental Design for a Thermometer, of which the following is a specification, reference being had to the accompanying drawing, forming a part thereof.

Figure I is a front view of a thermometer, showing our new design.

Fig. II is a side view of a thermometer, showing our new design.

We claim:

The ornamental design for a thermometer, as shown.

GEORGE S. CLARK.
PLUMMER B. SNYDER.
